Cyrus I. Knecht, Jr., Red Bank, N.J., assignor to Daniels
Plating Barrel & Supply Company, Linden, N.J.

Filed Jan. 2, 1970, Ser. No. 20,742

Term of patent 14 years

Int. Cl. D15—05

U.S. Cl. D55—1

*Fig. 3**Fig. 4*FIG. 1 is a perspective view of a plating barrel showing the new design;

FIG. 2 is an end elevation view thereof, the other end elevation being a mirror image thereof;

FIG. 3 is a bottom plan view taken approximately from the plane of the line 3—3 of FIG. 1; and

FIG. 4 is a greatly enlarged fragmentary transverse sectional view through a portion of the wall of the plating barrel looking toward one end thereof.

The partial disclosure of the appearance of the grate or screen elements is understood to be representative of the continuous appearance of the surfaces shown.

I claim:

The ornamental design for a plating barrel, as shown and described.
